UNITED STATES PATENT OFFICE.

CHARLES H. FREEMAN, OF BLOOMINGTON, ILLINOIS.

ECCENTRIC-DRIVEN PUMP.

1,314,322.

Specification of Letters Patent. Patented Aug. 26, 1919.

Application filed June 20, 1917, Serial No. 175,797. Renewed January 23, 1919. Serial No. 272,778.

To all whom it may concern:

Be it known that I, CHARLES H. FREEMAN, a citizen of the United States, residing at Bloomington, in the county of McLean and State of Illinois, have invented certain new and useful Improvements in Eccentric-Driven Pumps, of which the following is a specification.

This invention relates to eccentric driven pumps, and has for its object the production of an air pump, the pistons of which are driven by an eccentric secured upon a transverse shaft, the construction of the eccentric, the terminations of the pitmen, and the flanged cover plates are believed to be especially novel, and the combination of parts as a whole results in a particularly simple and effective air pump.

Of the accompanying drawings, wherein the construction of each part and its arrangement with respect to the others is fully illustrated, Figure 1 represents a side view of all parts assembled, showing the alined cylinders in section, and the pistons also in section longitudinally and vertically. In this figure the pitmen are also in line with each other upon the opposite sides of the eccentric. In this figure the flanged cover or retaining plate on the side of the eccentric presented toward the observer has been removed to disclose interior parts. Fig. 2 is a view similar to Fig. 1 with the eccentric turned upwardly and the pitmen inclined to each other. The near cover or retaining plate is partly broken away in this view. Fig. 3 is a rear view of the eccentric and the pitmen with one of the cover plates removed. Fig. 4 is a horizontal section taken upon the broken lines 4—4 of Fig. 3.

Throughout the drawings and description, the same letter is employed to refer to the same part.

Considering the drawings, the cylinders A and a, have the pistons B and b. The cylinders have their axes alined, and the shaft C passes transversely between them. The pistons are pivotally connected with the pitmen D and d.

Secured upon the shaft C is an eccentric E, which is provided with a central portion or hub e that projects on both sides of the eccentric.

As best shown in Figs. 1 and 3, the pitmen have curved, sliding terminations F and f, that fit the eccentric peripherally and slide thereon. The curved terminations of the

pitmen, as set forth in Fig. 4, extend beyond the pitmen bars on the sides thereof, and those terminations are held movably upon the periphery of the eccentric by means of flanged covers or retaining plates. The cover plate G has the annular flange g and a plurality of recesses in its rim, such as the cut away openings H and h. The cover plate G is on one side of the eccentric as best shown in Fig. 4, and the twin cover plate K is placed on the other side of the eccentric and secured by screws J engaging the screwholes j, as illustrated in Fig. 2. The cover plate K has the recesses k and k' in its rim, and the annular flange L. The two cover plates are alike. When the two cover plates are arranged and secured upon the sides of the eccentric as illustrated, their flanges cover the edges of the curved terminations of the pitmen and hold them in place movably upon the periphery of the eccentric.

In the operation of this invention, if it be assumed that the shaft and eccentric turn clockwise, starting from the positions of the parts set out in Fig. 1, the piston B will be withdrawn and the piston b moved inwardly with regard to their respective cylinders. The curved terminations of the pitmen slide upon the periphery of the eccentric, and the pitmen are inclined first upwardly and then downwardly, as will be readily understood.

Considering Figs. 1 and 3, it will be noted that the rim recesses H, h, and k, k', afford access into the spaces upon the inside of the flanges of the cover plates and between the ends of the curved terminations of the pitmen when the pitmen are alined as set out in those figures. In practice if those spaces or chambers so formed are filled with suitable grease, the operation of the pump will spread the same continuously over the meeting surfaces of the eccentric, of the curved terminations of the pitmen, and the inner surfaces of the annular flanges of the cover plates, thereby constantly lubricating the mechanism.

Having now described this invention and explained the mode of its operation, what I claim is:

1. The combination with a shaft, of an eccentric upon the shaft, the said eccentric having a hub projecting at the side thereof, a pitman, the said pitman having a curved sliding termination fitting the said eccentric externally, a retaining cover plate having

an annular flange arranged exteriorly with respect to the said curved sliding termination of the pitman, the said plate having a central opening fitting the said hub of the eccentric, and means for securing the cover plate and the said eccentric together.

2. The combination with a shaft, of an eccentric upon the shaft, the said eccentric having a hub projecting at the side thereof, 10 a pitman, the said pitman having a curved sliding termination fitting the said eccentric peripherally, a retaining cover plate having an annular flange arranged exteriorly with respect to the said curved sliding 15 termination of the pitman, the said plate having also rim portions cut away for admission of lubricant with the said flange of the plate and a central opening fitting the

said hub of the eccentric, and means for securing the cover plate and eccentric together. 20

3. The combination with a shaft, of an eccentric upon the shaft, the said eccentric having a hub projecting on both sides thereof, oppositely disposed pitmen, the said pitmen having curved sliding terminations 25 fitting the eccentric peripherally, retaining cover plates each having an annular flange arranged exteriorly with respect to the said curved sliding terminations of the pitmen, the said plates having central openings fitting the projecting portions of the said hub of the eccentric, and means for securing the cover plates and the said eccentric together. 30

In testimony whereof I affix my signature.

CHARLES H. FREEMAN.
